CHILD'S VEHICLE

Theodore N. Sneed, St. Louis County, Mo.

Application February 20, 1950, Serial No. 8,025

Term of patent 14 years

(Cl. D34—15)

To all whom it may concern:

Be it known that I, Theodore N. Sneed, a citizen of the United States, residing at St. Louis County, State of Missouri, have invented a new, original, and ornamental Design for a Child's Vehicle, of which the following is a specification, reference being had to the accompanying drawing forming a part hereof, in which:

Fig. 1 is a top plan view of a child's vehicle showing the new design;

Fig. 2 is a side elevational view of the vehicle; and

Fig. 3 is a front elevational view of the vehicle.

I claim:

The ornamental design for a child's vehicle, substantially as shown.

THEODORE N. SNEED.
